PINKING MACHINE

William T. Maxant, Ayer, Mass.

Application August 17, 1938, Serial No. 225,467

13 Claims. (Cl. 164—64)

This invention relates to an improvement in pinking machines of the type set forth in my prior patent, No. 1,984,224, granted December 11, 1934.

The object of this invention is to improve the construction of the pinking machine, as well as its operation, by the provision of anti-friction bearings for the cutter spindle and also for the anvil which cooperates with the cutter in a pinking machine of this type; the anvil and its bearings are removable from the cradle to facilitate replacement of any of these parts, the anvil being in the form of a roller having ball bearings journaling the same as a self-contained unit, which may be dropped into a milled opening in the cradle for easy removability and cleaning; guarding the cutter by an extension on the housing which partly surrounds the periphery of the cutter; providing a stripper which prevents the cloth from winding around the cutter shaft; providing a double adjustment for a cloth guide which extends on opposite sides of the cutter and may be adjusted to any desired angle and be locked in an adjusted position without danger of accidental displacement; securing the cutter on its spindle without a projection on the spindle through the cutter; and providing a bed plate that may be dropped into a standard sewing machine cut-out and which will enable the pinking machine to be applied to the usual sewing machine table and used therein.

In carrying out this invention, I have illustrated a preferred embodiment thereof in the accompanying drawings, in which:

Fig. 1 is a perspective view of my improved pinking machine;

Fig. 2 is a vertical sectional view therethrough, parts being in elevation;

Fig. 3 is a perspective view of the cloth stripper, detached;

Fig. 4 is a horizontal sectional view through the housing of the pinking machine, approximately on the line 4—4 of Fig. 2, and showing the casing in section and the other parts in plan;

Fig. 5 is a cross sectional view through the table and cradle, approximately on the line 5—5 of Fig. 2; and

Fig. 6 is a detail end elevation of a portion of the housing showing the stripper therein, parts being in section.

Although my improved pinking machine is designed for mounting on any suitable table or stand, it is especially constructed suitable for support on a standard sewing machine table which is designated generally by the numeral 1

in Fig. 1, within the usual sewing machine cut-out of said table.

The pinking machine comprises a bed plate 2 adapted to be seated upon the sewing machine table 1, and clamps 3 are arranged at the underside of the bed plate 2 in position to engage opposite sides of the sewing machine cut-out, as shown in Fig. 5. Each of the clamps 3 is carried by a pair of lugs 4 having slots 5 therein receiving adjusting screws 6 which extend through the lugs 4 and into the underside of the bed plate 2 for securing each clamp in an adjusted position. Upon loosening of the set screws 6, the clamps 3 may be adjusted laterally to different positions to accommodate for different sized cut-outs in various sewing machine tables, according to the width of the cut-out or opening therein, and to securely hold the pinking machine within said cut-out for operation on the sewing machine table.

The bed plate 2 carries a housing 7 which is cast integral therewith, preferably, and which is upstanding on the bed plate, with a fly wheel guard 8 at one end thereof.

Journalized within the housing 7 is a drive shaft 9 carrying a pulley 10 on the outer end thereof which receives a belt 11 that may be operated from the usual sewing machine drive. The inner end of the drive shaft 9 carries a pinion 12 meshing with a gear 13 on a cutter spindle 14 extending lengthwise in the housing 7. The opposite end portions of the cutter spindle 14 are journalized in cages of ball bearings 15 mounting in the housing 7 for free operation and to eliminate wear on the spindle. Openings 16 are provided in the housing 7 for lubricating the bearings of the shafts 9 and 14.

The inner end portion of the spindle 14 is reduced at 17, on which reduced portion is mounted the cutter 18 which has a serrated edge to accomplish the pinking operation. The length of the reduced portion 17 is less than the thickness of the cutter 18, so that said reduced portion on the spindle does not project through the cutter. In order to secure the cutter on the spindle, a set-screw 19 is provided which extends through the cutter and into the end of the spindle 14, as shown particularly in Fig. 2. This eliminates the necessity for a projection on the spindle through the cutter, which would interfere with the feeding of the cloth relative to the cutter, and it also prevents injury to the cloth which would result from a projected end of the spindle. The head of the set screw 19 is suitably rounded off so as to present a smooth surface.

The cutter 18 operates within a nose guard 20 which is substantially semi-cylindrical and projects lengthwise from the inner end of the housing 7, being rigidly secured thereto or integral therewith. This forms an effective guard for the cutter against injury to the operator.

A stripper 21 is arranged beside the cutter 18, generally in the relation shown in Figs. 5 and 6, in order to prevent the cloth from winding around the cutter spindle 14. The stripper 21 is carried by a wire frame 22, one end of which is inserted into the inner end of the housing 7, to which it is secured by a set screw 23.

Also mounted on the bed plate 2 beside the cutter 18 is a double cloth guide 24 which extends to opposite sides of the cutter 18, as shown in Fig. 4. Each opposite end of the double cloth guide 24 is provided with a lug 25 extending laterally thereof and seated upon the bed plate 2. Each lug 25 has a slot 26 therein receiving a set screw 27 that is threaded into the bed plate 2 to adjust the cloth guide 24 to any desired position with respect to the cutter 18. Thus the cloth guide may be adjusted to different parallel positions toward or away from the cutter 18, or adjusted to any desired angular position with respect thereto, according to the desired angle of cut relative to the material, and may be effectively locked in such adjusted positions without danger of turning therefrom, as would be the case if locked only at one side.

Mounted beneath the bed plate 2 and operating in cooperative relation with the cutter 18 is an anvil 28 in the form of a roller which projects through an orifice 29 in the bed plate and has its periphery bearing against the periphery of the cutter 18. The anvil 28 is mounted on a shaft 30 to which it is rigidly secured, and said shaft 30 rotates in a pair of ball bearings 31, each of which is a self-contained and enclosed assembly. The anvil 28 is supported by a cradle 32 having a slot 33 therein which receives the anvil 28, and at opposite sides of the slot 33 are seats 34 receiving the ball bearing assemblies 31. The assemblies 31 are removably seated in the seats 34 for ready removal therefrom with the anvil 28, the entire assembly being capable of being lifted out of the cradle 32 in order to replace the anvil or any of the ball bearings or for cleaning of these parts in a ready and simple manner. The cradle 32 is pivotally supported at 35 to a bracket 36 extending downwardly from the underside of the bed plate 2. The opposite end of the cradle 32 is seated upon one end of a leaf spring 37 which extends over a pin 38 intermediate its ends and on which it is capable of rocking, the opposite end of the leaf spring 37 being engaged by an adjusting screw 39 threaded through the bed plate 2. Upon turning down the adjusting screw 39, the inner end of the leaf spring 37 is turned upward, resiliently pressing the anvil 28 against the cutter 18.

The operation of the machine will be evident from the foregoing description, and from the accompanying drawings. The material is fed transversely over the bed plate 2 between the anvil 28 and the cutter 18, the latter being driven through its spindle 14, gears 12-13, drive shaft 9, pulley 10, and belt 11, from the driving mechanism of the machine or the standard sewing machine and the serrated edges of the cutter 18 produce the pinking effect on the cloth. The guide 24 guides the material into and through the machine, serving as a guide on both sides of the

cutter 18 and may be adjusted to any desired position.

It will be evident that either the cutter or the anvil may be driven positively and the other operated idly in engagement therewith. Thus the anvil 28 may be mounted on the spindle 14, if desired and be positively driven and the cutter be mounted in the cradle 32 in place of the anvil, the operation being otherwise the same.

The term "anti-friction" is used in the claims to distinguish from a plain surface friction bearing, even though lubricated, and to define the type of bearing unit containing ball-bearings, roller-bearings, and the like.

I claim:

1. In a pinking machine of the character described, the combination of a bed plate having a housing, cutting and anvil members having coacting edges arranged substantially at the upper surface of the bed plate, a spindle, a pair of longitudinally spaced sets of ball bearings journaling longitudinally spaced portions of said spindle in the housing, said spindle having an end projecting from said pair of sets of ball bearings and supporting the cutting member on said projecting end, and means for rotating said spindle.

2. In a pinking machine of the character described, the combination of cutting and anvil members arranged in coacting relation, a cradle receiving one of said members, supporting means for said cradle for bodily movement of said member toward and from the coacting member, said cradle having seats therein on opposite sides of said received member, and anti-friction bearing units removably mounted in said seats and journaling said member.

3. In a pinking machine of the character described, the combination of a support, a pair of cutting and anvil members mounted for rotary movement and having coacting edges, a cradle pivotally connected with the support, means resiliently urging said cradle upwardly, said cradle having seats in the upper side thereof on the opposite sides of one of said members, a pair of anti-friction bearing units mounted in said seats and bodily removable therefrom, and a shaft secured to said last-mentioned member and journaled in said anti-friction bearing units.

4. In a pinking machine of the character described, the combination of a bed plate, a pair of cutting and anvil members mounted for rotary movement and having coacting edges approximately at the surface of the bed plate, a cradle pivotally connected with the bed plate at the under side thereof, means resiliently urging said cradle upwardly toward the bed plate, said cradle having seats in the upper side thereof on the opposite sides of one of said members, a pair of anti-friction bearing units mounted in said seats and bodily removable therefrom, and a shaft fixed to the last-mentioned member and journaled in said anti-friction bearing units.

5. In a pinking machine of the character described, the combination of a bed plate, a pair of rotary superposed cutting and anvil members having coacting edges approximately at the upper surface of the bed plate, means for driving the uppermost one of said members, a cradle pivotally connected with the bed plate at the under side thereof and having a slot therein receiving the lowermost one of said members, said cradle having notched seats in the upper side thereof on opposite sides of said slot, anti-friction bearing units removably seated in said notched seats,

and a shaft fixed to the lowermost member and journaled in said bearing units for unitary removal therewith from the cradle.

6. In a pinking machine of the character described, the combination of a housing, cutting and anvil members, means mounting said members for rotary movement, and an approximately semi-cylindrical nose guard projecting inwardly directly from the end of the housing forming a continuation thereof with the peripheral surface of said guard in alignment with the peripheral surface of the housing, said nose guard extending about one of said members and forming a guard therefor.

7. In a pinking machine of the character described, the combination of a bed plate, a housing mounted on said bed plate, cutting and anvil members having coacting edges approximately at the surface of the bed plate, means mounting said members for rotary movement, and an approximately semi-cylindrical nose guard projecting inwardly directly from the end of housing forming a continuation thereof with the peripheral surface of said guard in alignment with the peripheral surface of the housing, said nose guard extending about one of said members and forming a guard therefor.

8. In a pinking machine of the character described, the combination of a bed plate, a housing on said bed plate, a spindle journaled in said housing and carrying a cutter on the inner end thereof, a stripper extending horizontally behind said cutter, and a wire frame extending over said spindle behind the cutter below the upper edge thereof and forming a continuation of the stripper with a backturned end engaging said housing, and means for rigidly securing said end of the frame to the housing.

9. In a pinking machine of the character described, the combination of a bed plate, coacting rotary cutting and anvil members operatively arranged with coacting edges thereof approximately at the surface of the bed plate, a cloth guide extending on opposite sides of said members transversely of the bed plate and mounted thereon, and means connected with each oppo-

site end portion of said guide for adjusting the angularity of the guide transversely relative to the rotary members and for locking said end portions in adjusted positions.

5 10. In a pinking machine of the character described, the combination of a bed plate, coacting rotary cutting and anvil members operatively arranged with coacting edges thereof approximately at the surface of the bed plate, a cloth guide extending on opposite sides of said members transversely of the bed plate and mounted thereon, said cloth guide having laterally extending brackets at each opposite end thereof on opposite sides of said members, said brackets being slideable transversely relative to the members to different parallel and angular positions of the guide relative thereto, and means for securing said brackets to the bed plate in different adjusted positions of the guide relative thereto.

15 20 25 11. In a pinking machine of the character described, the combination of a bed plate, cutting and anvil members having coacting edges substantially at the surface of the bed plate, a spindle, and a pair of longitudinally spaced anti-friction bearings journaling said spindle, said spindle having an end projecting from said pair of anti-friction bearings and supporting one of said members on said projecting end.

30 35 12. In a pinking machine of the character described, the combination of a bed plate, cutting and anvil members having coacting edges substantially at the upper surface of the bed plate, a cradle mounted on the bed plate at the under side thereof, and anti-friction bearing units journaling one of the members in the cradle.

30 35 40 45 13. In a pinking machine of the character described, the combination of a bed plate, cutting and anvil members having coacting edges substantially at the upper surface of the bed plate, a cradle mounted on the bed plate at the under side thereof and having transversely spaced seats in the upper side thereof, and anti-friction bearing units removably mounted in said seats and journaling one of the members in the cradle in position to bear against the coacting members.

WILLIAM T. MAXANT.
